UNITED STATES PATENT OFFICE.

ROBERT E. CROWLEY, OF GALION, OHIO.

SAFETY APPLIANCE FOR CAR-COUPINGS.

1,004,999.

Specification of Letters Patent.

Patented Oct. 3, 1911.

Application filed July 8, 1910. Serial No. 571,080.

To all whom it may concern:

Be it known that I, ROBERT E. CROWLEY, a citizen of the United States, residing at Galion, in the county of Crawford and State 5 of Ohio, have invented certain new and useful Improvements in Safety Appliances for Car-Couplers, of which the following is a specification.

This invention relates to the subject of 10 car couplings, and more particularly to safety attachments or appliances therefor to provide means whereby each coupler head supports the other against vertical displacement in the event of the breakage or pulling 15 out of either of the draw bars from its car.

To this end the invention has in view a simple, practical and thoroughly reliable safety attachment for car couplers which can be readily applied to the standard coupler 20 equipment without change or modification therein while at the same time positively safeguarding the train against those accidents which are due to breakage of the draw bars and the consequent uncoupling of the 25 cars and the dropping of the broken draw bar with its coupler to the track. Furthermore, under the condition of two cars being of unequal height at the point where they are to be coupled, the present invention provides 30 means which effectually prevents the cars from becoming uncoupled by one draw bar sliding out of the other or down below the other by reason of the inequality in height thereof. Also, it is a well known fact 35 that frequently in the use of the ordinary car couplers, where one coupler head is higher than the other, irregularities in the track likewise cause the cars to be uncoupled, with all of its attendant dangers 40 and damage, whereas the safety attachment of the present invention prevents these consequences by reason of the fact that one coupler head cannot slip through or out of the other coupler head, and an uncoupling 45 can only be effected in the usual way, viz.: by opening up the knuckles with the uncoupling appliances.

With these and many other objects in view, which will be readily apparent to 50 those familiar with the art, as the nature of the invention is better understood, the same consists in the novel construction, combination, and arrangement of parts hereinafter more fully described, illustrated and claimed.

55 The preferred and practical embodiment

of the invention is shown in the accompanying drawing, in which:

Figure 1 is a side elevation of a pair of car coupler heads equipped with the safety attachment contemplated by the present invention; the view showing one car coupler head dropped (as would be the case when its draw bar is broken or drawn out), and caught and supported from the other coupler head. Fig. 2 is a bottom plan view 60 illustrating two car coupling heads in their coupled relation and provided with the safety attachment claimed herein. Fig. 3 is a detail in perspective of the pivotal coupling knuckle provided with a safety 65 supporting bracket constructed and arranged according to the present invention.

Like references designate corresponding parts in the several figures of the drawings.

By way of illustrating the invention as 75 applied to a standard car coupler equipment without material change or alteration therein, there is shown in the drawings a pair of Janney-type car couplings each of which embodies in its organization the usual 80 coupler head 1, of the conventional form, the draw bar 2 carrying the coupler head, and the pivotal coupling knuckle 3. The coupling knuckle 3 has a pivotal mounting at one side of the coupler head upon the usual knuckle pin 4, and the free edge or nose 5 of the knuckle may or may not be provided with the usual holes 6 for a coupling pin, all of which is well understood by 85 those familiar with this class of couplings. Also, at one side of its pivotal point 4, the locking knuckle 3 is provided with the lock 90 or holding arm 7 coöperating with the usual locking and releasing devices of the coupling, but which devices form no part of the 95 present invention and are in no way affected or interfered with by the latter.

According to the present invention, it is proposed to associate with the pivotal knuckle 3 of each coupler head, a safety attachment of the character referred to, and this safety attachment essentially consists of a supporting bracket 8 depending from the bottom edge portion of the knuckle 3. The said supporting bracket 8 for each 100 knuckle consists of an upright shank member 9 having a rigid connection at its upper end, as at 10^a with the bottom edge of the knuckle between the pivotal point for the knuckle and the free edge or nose 5 thereof. 110

In new knuckles, the supporting bracket may be cast integral therewith, but in applying the attachment to old couplings, the upper end of the shank member 9 may be dovetailed or otherwise rigidly seated in the bottom edge of the knuckle as shown in the drawings, it only being necessary in any case to provide the rigid connection 10^a referred to.

10 In addition to the shank member 9, the supporting bracket includes, at the lower end of said shank member, a horizontally arranged widened holding step 10 which is rigidly formed with the shank member 9 and projects inwardly therefrom, that is to say, in an inward direction from the knuckle toward the back of the knuckle receiving recess formed in the front side of the coupler head. It will be observed that the said step 10 is of a flaring width and is preferably formed with a flat upper side so as to present a wide and substantial supporting surface upon which engages and rests the knuckle of the opposing coupler head.

15 20 25 In addition to the feature of the holding steps 10 being constructed of a flaring width to provide a wide and substantial supporting surface, a practical and important feature of the invention resides in the fact that 30 35 the flaring form of the steps 10 gives thereto a wedge shape which enables the steps to act positively as a means to assist in the opening and closing of the knuckles in the normal coupling and uncoupling operations. It will be observed that the steps 10 are so arranged as to occupy a close side by side relation when the two heads are coupled and the parts occupy the positions shown in Fig. 2 of the drawings. In such positions the flaring or wedge shape steps 10 may be said to be in interfering relation, but on account of the shape thereof, when the coupling heads are drawn apart in the uncoupling operation, the tendency of the engagement 40 45 50 55 of the opposing steps 10—10 is to kick or throw open the knuckles, thus greatly assisting in the uncoupling operation. Also, in the coupling operation of opposing coupler heads, the wedge shaped steps 10 come into engagement, upon their opposing wedge surfaces, and ride back to the positions shown in Fig. 2 with the result of assisting in turning the knuckles into their locked position.

55 By reason of the flaring width of the holding steps 10 of the opposing couplers

and the fact that the supporting members 9 are arranged intermediate the pivotal point and noses of the knuckles, and also by reason of the inward disposition of the steps 10 at substantially right angles to the vertical plane of the knuckles proper, several important advantages are secured. The principal of these advantages are that the steps 10 of opposing couplers have the action described in the normal coupling and uncoupling operations, besides maintaining a close, substantially parallel relation when the two heads are coupled as shown in Fig. 2 so as to act as braces against the torsional or twisting movement of the couplers. Furthermore, the arrangement described for the steps 10 provides means whereby when a coupler head drops for any of the causes mentioned the bottom corner of the nose of the knuckle of the broken coupler comes into supporting engagement directly on top of the step 10 of the other knuckle, thus securing a point of support in the most advantageous and effective position so as to positively prevents the falling down of the broken coupler or the twisting or slipping of the same out of place until uncoupled in the usual way. When the parts assume this position, that is the position shown in Fig. 1, the step 10, which is supporting the fallen coupler, has a lateral brace against the side of the shank member 9 carried by the fallen coupler.

I claim:

In a car coupling, the combination with the coupler head and the pivotal knuckle thereof, of a safety supporting bracket depending from the bottom of the knuckle between its pivotal point and the free edge thereof and provided with a horizontally arranged holding step projecting inwardly toward the front side of the coupler head and arranged to underlie the bottom corner of the nose of an opposing knuckle, said holding step being also of flaring or wedge form for striking engagement with the companion step to assist in the opening and closing of the knuckles of opposing coupler heads.

In testimony whereof I hereunto affix my signature in the presence of two witnesses.

ROBERT E. CROWLEY.
